ALTO CLARINET

Leon Leblanc, Paris, France, assignor to G. Leblanc Corporation, Kenosha, Wis., a corporation of Wisconsin

Application October 12, 1955, Serial No. 38,341

Term of patent 14 years

(Cl. D56—1)

Fig. 1 is a side elevational view of an alto clarinet embodying my new design; and

Fig. 2 is an enlarged fragmentary view of a portion of Fig. 1.

The dominant features of my design are shown in solid lines.

I claim:

The ornamental design for an alto clarinet, as shown and described.
